SUBSTITUTED AZACYCLOALKANES

Julius Diamond, Philadelphia, and William F. Bruce, Havertown, Pa., assignors to American Home Products Corporation, New York, N. Y., a corporation of Delaware

No Drawing. Application January 5, 1954,
Serial No. 402,397

2 Claims. (Cl. 260—239)

This invention relates to the preparation of cyclic compounds and more particularly to the preparation of acyl azacycloalkanes.

The compounds falling within the scope of the invention are specific members of the more general group of compounds and claimed in application Serial No. 297,185, filed July 3, 1952. The present compounds may be represented by the general formula

4-cyano-4-m-methoxyphenyl-N-methylazacycloheptane methochloride (Compound II).

wherein $>\text{X}$ stands for either $>\text{N}-\text{R}_1$ or

with R_1 representing a lower alkyl and R_2 standing for either hydrogen or an alkyl while A is an anion, R standing for an aryl group and with R_3 and R_4 each standing for hydrogen or lower alkyl and R_5 representing a lower alkyl group.

With regard to R which represents an aryl radical, the latter may be either a substituted or unsubstituted phenyl ring. Preferred substituents on a ring which may be in any position and ranging from 1 to 3 are lower alkyl, lower alkoxy, halogen, nitro, hydroxy, aliphatic acyl and acyloxy, amino and mono and di-lower alkyl-substituted amino radicals. As will be indicated later, an especially preferred radical because it imparts valuable therapeutic action to the compound is the m-hydroxy phenyl radical. In general, the compounds of the invention may be made in the manner disclosed in the earlier filed application Serial No. 297,185. A general procedure for making specific 4-acyl compounds utilizes the cyano compound obtained from Reaction 3 disclosed in said earlier case. In such general procedure, an ether solution of the alkyl mag-

nesium halide is prepared from 0.070 g.-atom of magnesium metal and 0.075 mole of alkyl halide in 100 ml. of dry ether. To this solution is added dropwise 0.05 mole of the appropriate 4-cyano compound in 100 ml. of toluene. The temperature is maintained, with stirring, at 25–35° C. during the addition. On its completion, the temperature is gradually raised by distilling off the ether. A maximum temperature of 65–85° C. is maintained for 6 hours. The mixture is cooled and extracted with dilute hydrochloric acid. The acid extract is washed with ether, then basified with ammonium hydroxide, and finally extracted with chloroform. The chloroform extract is dried over anhydrous sodium sulfate, filtered, and concentrated. Vacuum distillation of the residue gives the desired aminoketone base.

Acid addition salts of the cyclic bases may be made in well known manner as disclosed in Application Serial No. 297,185 by reacting the appropriate base with the desired inorganic or organic carboxylic acid. Preferred acids are those mentioned in said prior application. These cyclic bases are also capable of reacting with alkyl halides on an equimolar basis under normal conditions to form quaternary ammonium compounds.

The reaction is carried out in the presence of inert solvent. For a more specific description of the process, the following reactions illustrate the formation of the specific compound 4-propionyl-4-m-hydroxyphenyl-1-methylazacycloheptane.

25 $\text{m}-\text{CH}_3\text{O}-\text{C}_6\text{H}_4-\text{CHCH}_2\text{CH}_2\text{N}(\text{CH}_3)_2 + \text{BrCH}_2\text{CH}_2\text{CH}_2\text{Cl} \xrightarrow[\text{ether}]{\text{NaNH}_3} \text{m}-\text{CH}_3\text{O}-\text{C}_6\text{H}_4-\text{C}(\text{CN})-\text{CH}_2\text{CH}_2\text{N}(\text{CH}_3)_2$

Anal.—Calcd. for $\text{C}_{16}\text{H}_{22}\text{ClN}_2\text{O}$: C, 65.20; H, 7.86; N, 9.51; Cl, 12.03. Found: C, 65.71; H, 6.53; N, 9.51; Cl, 12.18.

*4-cyano-4-m-methoxyphenyl-N-methylazacycloheptane
(Compound III)*

Into a small Claisen flask set up for distillation, was placed 0.085 mole (25 g.) of the quaternary salt (II). After evacuating the system to 1-3 mm., heat was applied using an air-bath. At a bath temperature of 200-250° C. a liquid distilled over at 170-210° C. Redistillation gave the cyano base (III), B. P. 150-154° C. (0.3 mm.), n_D^{22} 1.5332, d_4^{22} 1.062.

Anal.—Calcd. for $C_{15}H_{20}N_2O$: C, 73.70; H, 8.25; N, 11.46; M_D 71.18. Found: C, 74.27; H, 8.58; N, 11.12; M_D 71.40.

4-propionyl-4-m-methoxyphenyl-N-methylazacycloheptane (Compound IV)

Ethyl magnesium bromide was prepared from 0.09 g-atom (2.2 g.) of magnesium metal and 0.10 mole (10.9 g.) of ethyl bromide in 150 ml. ether. To this solution was added, with stirring, 0.0573 mole (14 g.) of the cyano base (III) in 150 ml. of ether at such a rate as to maintain gentle refluxing. After 5 additional hours

with chloroform. The extract was dried, filtered, and distilled. At 190-200° C. (0.3 mm.) 3.3 g. of a yellow viscous syrup distilled over. On cooling the material became glassy. It was dissolved in boiling ether, filtered, and the filtrate concentrated to a small volume. On standing at room temperature, the product (V) appeared as white crystals. The mixture was filtered, the crystals washed with petroleum ether, and air dried. M. P. 135-6° C.; purple color with aqueous-alcoholic ferric chloride solution.

Anal.—Calcd. for $C_{16}H_{23}NO_2$: C, 73.50; H, 8.86; N, 5.36. Found: C, 73.92; H, 9.05; N, 5.53.

Other compounds falling within the scope of the invention are given in the following table with identifying characteristics. The various radials R , R_3 , R_4 and R_5 are specific species of the general formula given hereinbelow.

R	R_3	R_4	R_5	B. P. (0.3 mm.)	n_D^{20} (° C.)	Derivative, M. P.
C_6H_5	H	H	C_2H_5	132-6°	1. 5302 (26°)	methiodide, 217-9° d. hydrochloride, 122-5°.
C_6H_5	H	H	$n-C_7H_7$	132-3°	1. 5300 (26°)	picrate, 138-40°
C_6H_5	H	CH_3	C_2H_5	135-42°	1. 5350 (27.5°)	methiodide, 133-5°.
C_6H_5	CH_3	H	C_2H_5	133-42°	1. 6400 (27°)	picrate, 164-5° d.

of stirring and refluxing, the mixture was allowed to stand overnight. The cooled mixture was extracted with aqueous hydrochloric acid, the acid extract basified with ammonium hydroxide, extracted with ether, and the ether extract dried, filtered, and concentrated under reduced pressure. A light yellow liquid residue remained which contained the crude ketobase (IV).

*4-propionyl-4-m-hydroxyphenyl-methylazacycloheptane
(Compound V)*

The above compound (IV) was used without further purification. It was dissolved in 100 ml. of 48% hydrobromic acid. The solution was heated to reflux and kept at this temperature (110-125° C.) for 17 hours. The cooled solution was treated with 230 ml. of 4 N-sodium hydroxide solution and the resulting solution washed with ether. The aqueous alkaline solution was saturated with carbon dioxide to precipitate an oil which was extracted

35 The cyclic free bases are useful for the formation of quaternary ammonium compounds since they readily react with an alkyl halide, particularly the long chain alkyl halides, to form valuable wetting agents. These bases or their acid-addition salts are also capable of reacting with penicillin to form substantially water-insoluble salts thereof. In addition, many of the bases or their salts demonstrate varying degrees of analgesic action and thus are useful therapeutics.

40 We claim:

1. The compound, 1,2-dimethyl-4-phenyl-4-propionylazacycloheptane.
2. A compound of the group consisting of 1,2-dimethyl-4-phenyl-4-propionyl azacycloheptane and salts thereof.
